UNITED STATES PATENT OFFICE.

JOHN H. HARPER, OF RINGGOLD, TEXAS.

WIRE-STRETCHER.

1,219,306.

Specification of Letters Patent. Patented Mar. 13, 1917.

Application filed August 18, 1916. Serial No. 115,618.

To all whom it may concern:

Be it known that I, JOHN H. HARPER, a citizen of the United States, residing at Ringgold, in the county of Montague and State of Texas, have invented certain new and useful Improvements in Wire-Stretchers, of which the following is a specification.

This invention relates broadly to that class of inventions known as pushers and pullers.

The invention has more special reference to a wire stretcher the frame of which has means adjustably connected thereto for anchoring the frame in position on a post so as to permit of the convenient manual operation of the adjustable rack, on the frame carrying the wire clamping means.

More particularly the present invention has reference to the novel construction and arrangement of the means for adjusting the rack bar which although manually operable has the moving jaws so arranged in the frame that they will be alternately directed into engagement with the teeth of the rack bar during the swinging movement of the lever to which they are connected thus providing an efficient continuous adjustment on the rack bar.

It is the custom heretofore to provide means for actuating a slidable rack bar but these means have not accomplished the expeditious continuous adjustment thereof.

A further and more specific improvement resides in the provision of the novel construction of the frame provided with means for slidably supporting the rack bar, the latter being incidentally provided with stop means for limiting the outward movement of the bar.

Other means and novel details in the construction and arrangement of parts will be appreciated from the detail description below, which is to be read in connection with the accompanying drawings forming a part thereof and wherein I disclose the preferred embodiment of the invention for a purpose of illustration.

In the annexed drawings:—

Figure 1 is a longitudinal section of my invention.

Fig. 2 is a top plan thereof.

Fig. 3 is a transverse section taken on line 3—3 of Fig. 1 in the direction in which the arrow points.

Fig. 4 is an elevational detail of the wire clamp.

Referring more particularly to the drawings in which similar reference numerals designate like and corresponding parts throughout the several views, I provide a frame composed of a pair of complementary side bars 1 and 2 held in spaced parallel relation by means of transversely arranged blocks 3 positioned therebetween, the outer ends of each of the bars having offset portions to provide feet 4 which terminate in post engaging claws 5. Pivotedly mounted between the feet 4 are the spaced arms 6 of the laterally extending bracket 7. In order to adjustably anchor the frame on the post, I have provided a post engaging hook 8 the shank 9 of which is provided with a plurality of openings 10 removably engageable by a fastening device 11 on the bracket arms 6, it being desirable to arrange the shank 9 between the arms and fasten it in position after it has been anchored in the post in a manner so as to coöperate with the claws 5 illustrated in Fig. 1 of the drawings.

The inner surfaces of the bars 1 and 2 are provided with oppositely positioned longitudinally extending grooves 12 in which is slidably mounted a rack bar 13 having teeth 14 and 15 arranged on the opposite sides thereof and adjacent one longitudinal edge.

The wire clamping means in the present instance consists of a shank 16 the inner end of which is pivoted as at 17 to a block 18 carried by the inner end of the rack bar 13. The outer end of the shank 16 has a rigid jaw 19 formed thereon while a movable hand operable cam shaped jaw 20 is pivoted as at 21 to the outer end of the shank so that the cam portion of the jaw 20 will act in conjunction with the rigid jaw 19 and efficiently hold the piece of wire.

For the purpose of effecting an efficient continuous adjustment of the rack bar, I have provided the inner surface of one of the jaws 1 with V-shaped recesses 22 and 23 said recesses communicating at their vertices and at a point in alinement with the center of one of the grooves 12. The inner surface of the bar 1 is also provided adjacent one side of the recess 22 with another recess 24 the inner wall of the recess providing a curved shoulder for a purpose to be herein-after described. I have also provided another V-shaped recess 25 which extends from

the opposite side of the recess 22. The walls 26 of this recess 25 converge as they extend away from the recesses 22 and 23 and finally communicate with the adjacent groove 12.

5 Pivottally mounted through the medium of a suitable fastening device 27 is an operating lever 28 for the rack bar 13, said fastening device 27 being in alinement with the grooves 12. Complemental fingers 29 are

10 pivotally mounted by suitable fastening devices 30 through the operating lever 28 the fastening devices 30 being arranged below a fastening device 27 while the engaging ends of both of the fingers are curved and ar-

15 ranged within the recess 25 being directed into engagement with the teeth 14 and 15 by means of the converging walls 26 of the recess 25. The adjacent faces of the fingers 29 are enlarged to provide cams 31 one of

20 which is engageable with the curved shoulder of the recess 24 while the other is engageable with the correspondingly positioned shoulder 32 in alinement with the wall of the recess 23. It is thought to be

25 apparent that when the handle is moved toward the adjacent end of the frame that the inner finger will engage the teeth 14 while the outer finger moves rearwardly until its cam surface 31 strikes the shoulder 24 and

30 forces the curved engaging end into engagement with one of the teeth 15 whereupon the handle is swung in an opposite direction until this curved end abuts the adjacent wall 26 of the recess 25. During this movement

35 the cam surface 31 on the inner finger will strike the wall 32 and force the engaging end into engagement with the teeth 14, this operation being repeated until the bar traverses the length of the frame.

40 In order to limit the inward movement of the bar I have connected a stop 33 to one end thereof which engages the frame and prevents the displacement of the bar.

The operation of this invention is as fol-

45 lows:—

The claws 5 are engaged in a suitable post as is the hook 8 the latter being finally ad-

justably connected to the bracket 6 so that it will coöperate with the claws and hold the frame in position. A piece of wire is now 50 arranged between the jaws 19 and 20 and removably held in this position during the operation of the lever 28. While this lever is being swung back and forth and its movement limited by means of the recesses 22 55 and 23 the curved ends of the fingers will be alternately drawn into engagement by the cam surface thereof and continuously adjust the rack bar to which the clamping jaws are connected.

60 From the foregoing it will be understood that I have provided efficient means for continuously actuating the rack bar of a wire stretcher and particular stress is laid on this point together with the means for anchoring 65 the peculiarly constructed frame on the post.

Still further embodiments of the invention than those herein especially defined may be resorted to as conditions or preference may dictate, as may be in keeping with the 70 hereto appended claim.

I claim—

A wire stretcher including a frame embodying spaced side bars, means for anchoring the frame in position, a rack bar slidably mounted between the side bars, one of the side bars being provided with communicating V-shaped recesses, and further provided adjacent the sides of the V-shaped recesses with finger guiding recesses, a lever 75 pivotally mounted on one of the side bars and arranged within the V-shaped recesses, and fingers pivoted to the lever above and below the rack bar to alternately engage the teeth thereof and positioned within and 80 guided by the finger receiving recesses during the actuation of the lever.

In testimony whereof I affix my signature in presence of two witnesses.

JOHN H. HARPER.
